METHOD AND APPARATUS FOR
CRINKLING YARNFrederick W. Hole, Tiverton, Devon, England, assignor
to John Heathcoat & Co., Ltd., Tiverton, Devon, Eng-

land, a corporation of Great Britain

Filed June 30, 1965, Ser. No. 468,280
20 Claims. (Cl. 28—1)

This invention relates to a crinkling method and apparatus and, more particularly, a method and apparatus for crinkling yarns of a wide denier range.

It has been proposed to crimp or crinkle nylon and similar yarns composed of thermoplastic textile fibers by using movable sinker elements to force the yarn into slots or spaces between sinker blocks thereby to impart a crinkled configuration, after which the yarn is set by the application of heat while it is held in its crinkled condition. Sufficient heat is applied to raise the temperature of the yarn above its softening point, so that the yarn retains its crinkled configuration after cooling. This technique of setting thermoplastic yarns is in itself well known to the art.

Such prior art proposals have not been completely satisfactory because of the difficulty of forcing the yarn into slots or spaces in a moving crimp device without considerable dragging of the yarn over the following sinker elements which are in various stages of closure, inasmuch as the sinker elements would jam against a cam with a steep face. It has also been difficult in conventional crimping devices to withdraw the movable sinker elements sufficiently to permit the yarn to shrink during the setting operation. Yet another difficulty has been in arranging the sinker blocks and sinker elements sufficiently close together to permit a fine crimp to be obtained because of the guide slots needed for the reciprocating elements. Also, according to some prior art crimping devices both the sinker blocks and the sinker elements must be reciprocated, thereby increasing the complexity and cost of such equipment. Furthermore, the conventional crinkling devices generally employ positively driven reciprocating elements which act in one or possibly two planes. As a result, considerable adjustment is required before a yarn of substantially different denier may be crinkled, and the character of the crinkle obtained is not always satisfactory.

Accordingly, it is an object of the present invention to overcome the above-mentioned difficulties of conventional systems for crinkling yarn.

Another object of the invention is to provide a novel method and apparatus for crinkling yarn of a wide denier range.

These and other objects and advantages of the invention are attained by a method including the following series of steps. A thermoplastic yarn to be crinkled is fed to a rotatable crimping head which includes a plurality of mutually spaced apart sinker blocks which are fixedly mounted on the head for rotation therewith. A plurality of sinker elements mounted on the head are adapted to be moved between closed positions between the sinker blocks and open positions away from the sinker blocks. The yarn is introduced between the sinker blocks and the sinker elements when the elements are in their positions. Then the sinker elements are sequentially closed to entrap the yarn in a crinkled state between the blocks and the elements. The yarn is heated to a softened state while it is so entrapped, and the elements are then sequentially opened to release the yarn. The apparatus according to the invention may also be used to crinkle yarns chemically by thermosetting, or mechanically by plastic deformation for fibers having a sufficient degree of cold flow. In this last case no heat would be applied to the yarn.

2

In the preferred form of the invention the sinker elements are pivotally mounted so that each such element is rotated into and out of a different one of the spaces between adjacent sinker blocks.

5 All of the above is more fully explained in the detailed description of a preferred form of the invention which follows, this description being illustrated by the accompanying drawings wherein:

FIGURE 1 is a schematic view of part of a yarn processing apparatus including the yarn crimping apparatus according to this invention;

FIGURE 2 is an enlarged elevational view of a guide and feed roller of the yarn processing apparatus of FIGURE 1;

FIGURE 3 is a perspective view of a portion of the guide of FIGURE 2;

FIGURE 4 is an enlarged perspective view of the crimping apparatus of FIGURE 1;

20 FIGURE 5 is a plan view of the apparatus of FIGURE 4;

FIGURE 6 is a cross-sectional view taken along the line 6—6 of FIGURE 5 and looking in the direction of the arrows;

25 FIGURE 7 is a side elevation of the apparatus of FIGURE 5;

FIGURES 8 and 9 are enlarged elevation and plan views of sinkers forming part of the apparatus of FIGURE 4;

30 FIGURE 10 is an enlarged perspective view of a cam forming part of the apparatus of FIGURE 4; and

FIGURE 11 is an enlarged perspective view of the sinker closing assembly of the apparatus of FIGURE 4.

Referring first to FIGURE 1 of the drawings, a yarn 21 which may be composed of thermoplastic textile fibers is, in the exemplary yarn processing apparatus 20 according to this invention, drawn off from a creel 22 and passed through a conventional yarn tensioning device 23 which is in itself well known to the art. The tensioner 23 includes an input guide 24 and an output guide 25. It then passes via a feed roller guide 28 to a feed roller 29 which is driven by a drive roller 30. The yarn passes through a U-shaped portion 31 (FIGURES 2 and 3) of the feed roller guide 28, around the feed roller 29, over a hook portion 32 of the guide 28, and again around the feed roller 29 to a guide 40. A depression 33 formed in the hook 32 prevents the yarn from accidentally falling off the hook. The yarn thus makes one and one-half loops around the feed roller and is engaged between the feed roller 29 and the drive roller 30 twice. This treading arrangement of the yarn over the guide 28 and feed roller 29 enables the yarn to be advanced by the drive roller 30 at the desired predetermined speed.

55 The yarn then passes over a conventional pre-oiling roller 42 to a yarn crimping apparatus 45. The roller 42 is mounted for rotation in an oil-containing bath 43 so as to transfer oil from the bath to the yarn 21 in order to accomplish the lubrication or dampening thereof, if desired. The roller 42 and bath 43 may be omitted for yarns of light denier. They may also be used to apply a suitable chemical setting agent to the yarn if the yarn is to be set chemically.

60 The yarn is fed to the crimping apparatus 45 through an inlet guide 47 and then passes around the interior of the crimper 45. The yarn is crimped or crinkled as it travels through the crimper and it leaves the crimper through an outlet guide 48. From the guide 48 the yarn passes over a V-shaped guide 49, the position of which may be adjusted relative to the crimper 45 as necessary to permit the yarn to cool sufficiently, if heat was applied thereto in the crimper. The yarn then passes through a trip wire 50 of a suitable electric stop motion switch 51, and a pair of guides 53 and 54 which control the path

of the yarn over a suitable oiling roller 55. The yarn is then fed over a guide 57 and around a take-up tube 58, which is driven by a take-up drive roller 60, the tube being rotatably mounted on a pair of arms 61. The drive rollers 30 and 60 are coupled to the drive means (not shown) for the crimper 45, and the stop motion switch 51, insures that the drive means to the crimper is disengaged or is de-energized through conventional circuitry known to the art in the event that the yarn goes too slack or breaks between the crimper and the take up tube. The stop motion switch 51 is also a manual switch which can be used to disengage the crimper to facilitate threading up the yarn.

The crimping apparatus 45 (FIGURES 4 to 7) includes a housing 62 containing a shaft 63 rotatable in anti-friction bearings 64 and driven by a sprocket 65 connected to the drive means (not shown), while a handle 66 is provided to permit the shaft 63 to be rotated manually if desired. A plurality of sinker blocks 70 are mounted on a supporting plate 71 which is secured to and rotatable with the shaft 63. The sinker blocks are arranged in a circle to provide a plurality of radial spaces, a plurality of spacers 72 holding the blocks 70 perpendicular to the supporting plate 71. A sinker locating ring 74 holds the blocks in the desired radial position, each sinker block 70 being formed with a notch 75 (FIG. 8) for receiving the ring 74. A cut-away portion 76 in the supporting plate 71 permits the free movement of the ends of the sinker blocks 70 without twisting, and also facilitates the removal of any deposits.

A plurality of movable sinker elements 78 are pivotally mounted by their inner ends in the spaces between the fixed blocks 70 so that the outer ends of the elements 78 can move to and from the supporting plate 71 between a closed position in which the free ends of the sinker elements 78 are engaged in the spaces between the fixed blocks 70 and an open position in which they are disengaged from the spaces. More specifically, each of the sinker elements 78 is mounted for rotation into and out of a different one of the spaces between adjacent ones of the fixed sinker blocks 70. The fixed blocks 70 and the movable elements 78 may be made from thin sheet metal, for example.

Each sinker element 78 is provided at its inner end with a notch 80 (FIGURE 8) which makes a loose fit with the ring 74, so that the elements 78 are hinged on the ring 74. The inner ends of the elements 78 are retained in the spaces between the sinker blocks 70 by a sinker retaining plate 82, a notch 83 at the inner end of each element 78 insuring the free rotation thereof. The retaining plate 82 also holds the fixed blocks 70 securely against the supporting plate 71. The movable elements 78 are also rotatable with the plate 71, and the fixed sinker blocks 70, the plate 71 and the movable sinker elements 78 comprise a rotatable crimping head 85. As the crimping head rotates, the sinker elements 78 are caused to move between their open and closed positions by an arrangement of cams now to be described.

The cam arrangement comprises an opening cam 88 (FIGURES 4 and 5) including a ramp portion 89 which is engaged by a step 91 (FIGURES 6 and 8) formed in the outer end of each element 78 and which is shaped to cause the elements 78 to swing to their open positions so that these elements are open at the angular positions of the crimping head at which the yarn is to be supplied to, or withdrawn from, the crimping head. The outer end of each sinker block 70 has a cut-away portion 93, and the yarn is fed into the notch formed between the portion 93 of the blocks 70 and the corresponding sinker elements 78. The cam arrangement also includes a closing cam 95 (FIGURES 4, 10 and 11). A rod 97 extending from the cam 95 is received in a bore 98 in a shaft 99 which is rotatably mounted in an arm 100 carried by the housing 62. This cam 95 has a "lead-in" edge 104 the inclination of which relative to the fixed sinker blocks

70 can be adjusted by rotation of a cam pin 106 which is mounted on the arm 100. The pin 106 is formed with an eccentric shoulder 107 (which is exaggerated for clarity in FIGURE 11) so that rotation of this pin in the proper direction adjusts the inclination of the edge 104 as required, the shoulder 107 engaging a rocker arm 109 which is secured to the shaft 99. A set screw 110 holds the pin 106 in any position to which it has been adjusted.

When the crimping head 85 is rotated in the direction shown by the arrow 111 (FIGURE 4), the movable elements 78 are sequentially engaged by the "lead-in" edge 104 of the cam 95 and are rotated into the corresponding spaces between the sinker blocks 70. In particular, each movable element 78 is engaged by the cam 95 between the notch 80 and the step 91 as close to the notch 80 as possible, so that a mechanical advantage is developed whereby the outer end of each movable element moves a substantially greater distance than the portion of the element which engages the cam. Each of the sinker blocks 70 is formed with an intermediate joggle 113 which engages the movable elements 78 to guide them between the blocks 70 without producing a rubbing or a shearing action which might cut or abrade the yarn.

The cam 95 is provided with a roller 114 of small diameter arranged to complete relatively quickly the movement of the sinker elements 78 into the spaces between the blocks 70. In this way the yarn is forced into a particular space without being dragged over the following sinker elements 78 which are engaging the lead-in edge 104. The cam 95 has an edge 116 on the opposite side of roller 114 from the "lead-in" edge 104 which serves to hold the elements 78 closed until a sufficient number of elements are closed so that rotation of the head 85 will pull the yarn without slippage. The pivots of the sinker elements 78 are so arranged that thereafter these sinker elements are held closed by centrifugal force until they are opened by the cam 88. The crimping head 85 is rotated at such a speed that the centrifugal force does not prevent the yarn from shrinking as it sets while entrapped between the sinker blocks 70 and the sinker elements 78.

The arm 100 (FIG. 4) is slidably supported on the housing 62 and is provided with a slot 118 in which is engaged a flange 119 of a flanged screw 120. Rotation of this screw causes movement of the arm 100 in its slides 45 thereby to adjust the position of the cam 95 with respect to the sinker elements 78 and consequently the depth to which this cam drives these elements into the spaces between the sinker blocks 70.

The cam 95 is permitted to rock away from the sinker closing position against the action of a spring 124 whenever the space between the sinker elements 78 and the sinker blocks 70 is blocked by two much yarn. This will cause an abutment 126 formed in the rocker arm 109 to engage an adjustable contact 128 and thereby ground an electric circuit (not shown) connected to a terminal 130 to disengage a driving clutch (not shown) of the drive means for the crimping head 85. Thus, the crimping apparatus will automatically be shut down when it is overloaded. The free movement allowed to the cam 95 before the terminal 130 is grounded is determined by the position of the adjustable contact 128.

As each sinker element 78 approaches a predetermined angular position with respect to the housing 62, it is caused by the opening cam 88 to swing to its open position to permit yarn to enter through the inlet guide 47 between that element 78 and the adjacent fixed blocks. Continued movement of the head 85 then causes the element 78 to be moved to its closed position by the cam 95 thereby to entrap the yarn in the space between the element 78 and the sinker block on each side of it. As the yarn is sandwiched between the outer ends of the sinker blocks they tend to move apart, and the cut-away portion 76 permits this movement to take place without restraint from the supporting plate 71. Due to the novel

manner in which the elements 78 are pivotally mounted, the sections of the yarn between adjacent sinker blocks are twisted while being forced into the spaces between these blocks, thereby imparting a desirable crinkle to the yarn. From 5 to 40 or more V-shaped crimps may be made in each inch of yarn by the novel arrangement of the sinker blocks and sinker elements. The elements 78 remain in the closed position for the desired period of time after which they are again opened by the cam 88 to permit the yarn to be released through the outlet guide 48. While the yarn is in its entrapped state, it is heated to a temperature above its softening point by a suitable electric heater 134 (FIGURE 6), the temperature of which is controlled by a suitable temperature sensing element 135 through any appropriate circuitry (not shown) well known to the art. A pair of enclosure plates 137 and 138 are preferably formed of a suitable heat insulating material in order to facilitate the proper heating of the yarn.

A representative list of some types of yarn which may be crinkled by this apparatus follows, as well as the range of temperature and the preferred temperature to which each yarn is heated.

Composition of Yarn	Preferred Temperature, °C.	Temperature Range
Lurex metallic ribbon.....	(1)	To fusing temperature.
Dacron.....	200	80° C. to 240° C.
Nylon 66.....	185	80° C. to 240° C.
Acetate.....	165	Room temperature to 190° C.
Resin treated cotton.....	200	Depends on resin.
Lurex polyester ribbon.....	175	Room temperature to 195° C.

¹ Room temperature.

While the fundamental novel features of the invention have been shown and described, it will be understood that various substitutions, changes and modifications in the form and details of the apparatus illustrated and its manner of operation may be made by those skilled in the art without departing from the spirit of the invention. For example, the guides 47 and 48 may be provided with a plurality of eyes for guiding several yarns simultaneously through the crimping head 85, additional cut-away portions being provided in the sinker elements as necessary. Also, this crimping apparatus may be used to crimp other yarns which do not require heat to be set, as mentioned above, in which case the electric heater may be omitted or disconnected from its source of electrical current. All such variations and modifications, therefore, are included within the intended scope of the invention as defined by the following claims.

I claim:

1. Apparatus for crinkling yarn comprising:
a plurality of fixed, mutually spaced apart sinker blocks,
a plurality of pivotally mounted sinker elements which are adapted to be rotated between closed positions in which they occupy the spaces between the fixed sinker blocks and open positions in which they are disengaged from the spaces and outside a plane through said sinker blocks,
means for rotating the rotatable sinker elements to the open positions,
means for introducing the yarn between the fixed sinker blocks and the rotatable sinker elements when the sinker elements are in the open positions,
means for rotating the rotatable sinker elements to the closed positions to entrap the yarn in a crinkled state between the sinker blocks and the sinker elements, and
means for withdrawing the yarn from the sinker blocks and the sinker elements when the sinker elements are in the open positions.

2. Apparatus according to claim 1 including rotatable support means upon which the sinker blocks are fixedly mounted and the sinker elements are pivotally mounted, and drive means for rotating the rotatable support means.

3. Apparatus for crinkling yarn comprising:
rotatable support means,
drive means for rotating the rotatable support means,
a plurality of mutually spaced apart sinker blocks fixedly mounted on the rotatable support means,
a plurality of sinker elements pivotally mounted on the rotatable support means, each of the sinker elements being mounted for movement between a different pair of adjacent sinker blocks, the sinker elements being adapted to be rotated between closed positions in which they occupy the spaces between the sinker blocks and open positions in which they are withdrawn from the spaces,
first cam means for engaging the sinker elements sequentially and rotating them to their open positions, means for introducing the yarn between the sinker blocks and the sinker elements when the sinker elements are in the open positions,
second cam means for engaging the sinker elements sequentially and rotating them to their closed positions to entrap the yarn in a crinkled state between the sinker blocks and the sinker elements, and means for withdrawing the yarn from the sinker blocks and the sinker elements when the sinker elements are in their open positions.

4. Apparatus according to claim 3, wherein the sinker blocks and the sinker elements are disposed radially about the axis of rotation of the rotatable support means, and the sinker elements are pivotally mounted at their inner ends.

5. Apparatus according to claim 4, wherein the first cam means engages the sinker elements at their outer ends.

6. Apparatus according to claim 4, wherein the second cam means engages each sinker element at a point intermediate the inner and outer ends, whereby the outer end of the element is rotated a greater distance than the intermediate point thereof.

7. Apparatus according to claim 4, wherein the sinker blocks are provided with notches at their outer ends for receiving the yarn.

8. Apparatus according to claim 3, including guide means for spacing the yarn-engaging portion of each sinker element from the yarn-engaging portions of the adjacent sinker blocks when the sinker element is in its closed position.

9. Apparatus according to claim 3, wherein the sinker elements are so pivoted that they are normally held in their closed positions by centrifugal force when the support means is rotated.

10. Apparatus according to claim 3, including means for advancing the yarn to the introducing means at a predetermined speed.

11. Apparatus according to claim 3, including means for setting the yarn while it is entrapped in the crinkled state between the sinker blocks and the sinker elements.

12. Apparatus according to claim 11, wherein the setting means includes heating means.

13. Apparatus according to claim 3, including means for applying a chemical setting agent to the yarn.

14. Apparatus according to claim 3, wherein the second cam means includes roller means for completing the movement of the sinker elements to their closed positions.

15. Apparatus according to claim 3, wherein the second cam means is so shaped to retain a plurality of the sinker elements simultaneously in their closed positions.

16. Apparatus according to claim 3, wherein the second cam means is adjustably mounted with respect to the sinker elements to permit adjustment of the extent to which the sinker elements are rotated into the spaces between the sinker blocks.

17. Apparatus according to claim 3, wherein the second cam means includes a camming surface adapted to engage the sinker elements, and is adapted to be adjusted to vary the inclination of the camming surface with respect to the direction of travel of the sinker blocks.

18. Apparatus according to claim 3, including means for biasing the second cam means in a desired position, a first electrical contact coupled to the second cam means, and a second electrical contact disposed in spaced cooperative relation to the first contact, whereby the second cam means may be driven by a sinker element from the desired position against the biasing means to close the first and second contacts and effect the deenergization of the drive means.

19. A method for crinkling yarn comprising the steps of:
 feeding the yarn between a plurality of mutually spaced apart fixed sinker blocks and a plurality of pivotally mounted sinker elements,
 rotating each sinker element into the space between a different pair of adjacent sinker blocks from a position outside a plane through said sinker blocks to entrap the yarn in a crinkled state between the sinker blocks and the sinker elements,
 setting the yarn while it is in the crinkled state,

5
 20. A method for crinkling yarn comprising the steps of:
 simultaneously forcing the yarn into the spaces between a plurality of mutually spaced apart sinker blocks while twisting the sections of yarn between adjacent sinker blocks into a crinkled state, and setting the yarn while it is in the crinkled state.
